PUMP DEVICE

George R. Ericson, Kirkwood, Mo., assignor to
 Carter Carburetor Corporation, St. Louis, Mo.,
 a corporation of Delaware

Application April 17, 1937, Serial No. 137,427

2 Claims. (Cl. 261—34)

This invention relates to fluid pumps and consists, particularly, in novel accelerating pump structure for carburetors.

An object of the invention is to provide novel means for attaining delayed action discharge from the pump or, in other words, means for continuing the pump discharge after the actuating member has come to rest.

Another object is to provide novel means for providing delayed action discharge from the pump while, at the same time, insuring a substantial initial discharge therefrom. These objects and other more detailed objects hereafter appearing are attained by the structure illustrated in the accompanying drawing, in which:

Fig. 1 is a sectional view of an internal combustion engine carburetor embodying a form of the invention and

Fig. 2 is a view of a slightly modified part in a different position.

The carburetor shown comprises a downdraft mixture conduit including air inlet horn 1, venturis 2, and outlet part 3 flanged as at 4 for attachment to the intake manifold, not shown, of an associated engine. A choke valve 5 is pivotally mounted in the air horn and throttle valve 6 is pivoted near the outlet portion on shaft 7. Any suitable means (not shown) may be provided for operating the choke and throttle valves. Adjacent the mixture conduit is a bowl 8 within which fuel is maintained at a substantially constant level by the usual needle valve and float mechanism (not shown).

Also located within the float bowl is an accelerating pump cylinder 9, slidably receiving a cup-shaped piston 10 which is constantly urged upwardly by coiled spring 11 compressed between the bottoms of the piston and cylinder. Fuel enters the pump cylinder from the bowl through a screened inlet passage 12 controlled by check 13 and is discharged past outlet check 14 through a nozzle 15 into the mixture conduit adjacent the venturis. The inlet and outlet checks communicate with cylinder 10 through a passage 16.

Pump piston 10 is connected to the throttle valve through the intermediary of piston rod 17 and lever 18, pivoted to pillow block 19 projecting above the float bowl cover and connected to crank 20 rigid with the throttle shaft by means of a link 21. The lower portion of piston rod 17 is telescopically received within the hollow interior of piston 10 and is connected to the piston by means of spring 22 which, at its lower end, is secured directly to the free end of rod 17 and at its upper end is secured in a groove near the

upper extremity of the piston. Spring 22 is closely wound in a manner to have inherent initial tension so that even slight opening movement of the throttle valve will apply substantial force to the pump piston tending to move the same in the discharge direction against spring 11. Spring 11 preferably, is substantially weaker than spring 22 so that the pump piston will respond immediately to opening of the throttle. Due to its inherent initial tension, spring 22 may be made of substantially lighter material than would be the case if the spring were otherwise formed. Such a spring exerts a more nearly constant force as it returns to its initial shape than a heavier spring at no initial compression and produces more uniform delayed pumping action.

In case the throttle is opened slowly, piston 10 will move downwardly in the cylinder at a corresponding rate and insufficient pressure will result in the pumping chamber to cause extension of spring 22. However, if the throttle is opened quickly, the substantially increased pressure produced within pumping chamber, due to restrictions in the outlet passages, will cause distortion of spring 22 to permit telescoping movement between piston rod 17 and the piston. At the end of the movement of actuating rod 17, spring 22 will contract to its original shape producing continued discharge movement of piston 10.

Fig. 2 shows a conical spring 22a, connecting piston rod 17 with the pump piston 10, in place of the cylindrical spring in the previous figure. The spring in this form is also of the closely wound, initially stressed variety, but is shown in the extended shape it assumes in case of rapid opening of the throttle valve.

The yielding pump structure described is stable due to the closely wound character of the spring connecting the piston with its actuating member and also insures substantial initial and desirably uniform delayed action of the pump. Due to the construction of the spring, substantial pressure must be produced in the pumping chamber before spring 22a is extended.

The pistons in both forms are of the metal type with circumferential grooves, but any suitable type of piston may be used. Also it may be convenient to form the piston as a collar having a center aperture receiving the piston rod, rather than cup-shaped as shown, but in such case the plunger collar must be sufficiently thick to insure stability within the cylinder.

The invention may be modified in these and

other respects as will occur to those skilled in the art and the exclusive use of all such modifications as come within the scope of the appended claims is contemplated.

5. I claim:

1. In a carburetor, means forming a mixing conduit, a throttle valve for controlling the flow of mixture therethrough, an accelerator pump including a cylinder and piston for supplying accelerating charges to said mixing conduit upon opening movement of said throttle, a connection between the throttle valve and said piston including a piston rod, a connection between said piston and piston rod comprising an initially tensioned closely wound coiled spring, one end of which is secured to said piston and the other end to said piston rod, whereby initial movement of said throttle at a moderate rate will produce a substantially simultaneous corresponding movement of said piston in the discharge direction, and an excessively rapid movement of said throttle will partially extend said spring to permit lagging and gradual movement of said piston, and a continued discharge from said accelerator pump after completed movement of said piston rod, by virtue of continued movement of the piston to full discharged position due to energy stored by the extension of said initial tensioned spring.

terminated by the yielding of said spring, by virtue of energy stored in said spring by said yielding movement.

2. In a carburetor, means forming a mixing conduit, a throttle valve for controlling the flow of mixture therethrough, an accelerator pump including a cylinder and piston for supplying accelerating charges to said mixing conduit upon opening movement of said throttle, a connection between the throttle valve and said piston including a piston rod, a connection between said piston and piston rod comprising an initially tensioned closely wound coiled spring, one end of which is secured to said piston and the other end to said piston rod, whereby initial movement of said throttle at a moderate rate will produce a substantially simultaneous corresponding movement of said piston in the discharge direction, and an excessively rapid movement of said throttle will partially extend said spring to permit lagging and gradual movement of said piston, and a continued discharge from said accelerator pump after completed movement of said piston rod, by virtue of continued movement of the piston to full discharged position due to energy stored by the extension of said initial tensioned spring.

GEORGE R. ERICSON.
